UNITED STATES PATENT OFFICE.

CHARLES D. MONTAGUE, OF RIDGEWOOD, NEW JERSEY, ASSIGNOR TO THE GENERAL MANIFOLD AND PRINTING COMPANY, OF FRANKLIN, PENNSYLVANIA, A CORPORATION OF PENNSYLVANIA.

MULTIFORM BILLING-SHEET.

1,202,087.

Specification of Letters Patent. Patented Oct. 24, 1916.

Application filed December 10, 1914. Serial No. 876,394.

To all whom it may concern:

Be it known that I, CHARLES D. MONTAGUE, a citizen of the United States, and a resident of Ridgewood, in the county of Bergen and State of New Jersey, have invented certain new and useful Improvements in Multiform Billing-Sheets; and I do hereby declare that the following is a full, clear, and exact description thereof, reference being had to the accompanying drawings, and to the letters of reference marked thereon, which form a part of this specification.

This invention relates to an improved multiform billing sheet and consists of the matters hereinafter described and more particularly pointed out in the appended claims.

The object of the invention is to produce a multiform billing sheet which is so constructed and arranged that a number of copies may be made at the one writing, and if desired, a copy produced on a record sheet separate from the multiform bill sheet, and which may be so folded that but one folded edge is presented to the platen when the bill is inserted in a typewriter.

The improved bill is provided on certain sections with transfer material so that the use of interposed carbon sheets is dispensed with.

The improved bill is of particular advantage for use in connection with the business of public utilities or public service corporations where there are required for example, in addition to the original bill, collection sheets, cashier's copies, ledger sheets, meter readers' copies, and the like. The bill is so printed that the particular forms required for the different purposes appear on the several sections of the bill sheet and the sections provided with the carbon transfer material may be so blocked out that when desired all or only parts of the matter written on the original bill may be made to appear on either or any of the several copies.

The various advantages of my invention will appear as I proceed with my specification.

In the drawings: Figure 1 is a perspective view of a multiform billing sheet made in accordance with my invention, as it appears when folded and ready to be written upon. Fig. 2 is a transverse section on an

enlarged scale through my improved bill form when folded, the plane of the section being indicated on lines 2—2 of Fig. 1. Fig. 3 is a front face view of my improved billing sheet prior to the folding thereof. Fig. 4 is a face view of the reverse side of the sheet. Figs. 5, 6, 7, 8 and 9 respectively are diagrammatic views illustrating the manner in which the sheet is folded upon itself.

Referring now to that embodiment of my invention illustrated in the accompanying drawings, 10 represents the multiform billing sheet as a whole. (See Fig. 3.) Said sheet is divided into a plurality of substantially equal sections by transverse lines 11 of perforation, scoring or other weakening means. As shown there are eight of said sections, indicated by the numerals 12, 13, 14, 15, 16, 17, 18 and 19 respectively. Several of said sections, viz: the sections 13, 14, 16, 17 and 18 are printed upon one side or the other with the desired ruled forms, 13^a, 14^a, 16^a, 17^a and 18^a respectively and may have also printed thereon any such matter as may be required in the particular use to which the bill form as a whole is to be put.

The forms 13^a and 17^a on the sections 13 and 17 respectively are printed on the front or obverse face of the sheet and are arranged with their heads toward the top of the sheet 85 so as to be read from the top to the bottom of the sheet. The forms 14^a, 16^a and 18^a on the sections 14, 16 and 18 respectively are printed on the reverse side or back of the sheet and are arranged with their heads 90 toward the bottom of the sheet.

The sections 12 and 16 of the sheet 10 are provided on their front faces with a coating of carbon or like transfer material 12^x and 16^x respectively. The reverse sides of the sections 13, 15 and 19 are likewise provided with carbon coatings 13^x, 15^x and 19^x respectively. The front faces of the sections 14, 15, 18 and 19 respectively are blank and the reverse sides of the sections 10 and 17 100 are likewise left blank.

The sheet is folded in the following manner to bring the various sections in their proper superposed relation:—That part of the sheet comprising the first three sections 105 12, 13 and 14, respectively, is folded back upon the remainder of the sheet along that line of perforation 11 dividing the third and

fourth sections 14 and 15 respectively, so as to overlap the sections 17, 16 and 15 respectively. (See Fig. 6.) With the sections in this position the carbon coating 13^x on the 5 section 13, engages the printed bill form 16^a of the section 16. That part of the sheet comprising the seventh and eighth sections 19 and 18 respectively is then folded back, about that line of perforations 11 dividing 10 the sixth and seventh sections, 18 and 17 respectively, so as to overlap the first and second sections 12 and 13 respectively, with the carbon coating 19^x engaging against the printed bill form 13^a on the section 13. (See 15 Fig. 7.) Next in order or the third fold, that part of the sheet comprising the third and fourth sections 14 and 15 respectively is folded back upon the already folded sections of the sheet so as to overlie the sections 19, 13 and 16 respectively with the carbon coating 15^x in engagement with the bill form 14^a of the section 14. This fold brings the third section 14 against the reverse side of the eighth section 19. (See Fig. 8.) The 20 two parts thus left are folded along the line 11 dividing the fifth and sixth sections so that, that part of the sheet comprising the superposed sections 17, 12 and 18 respectively overlies the superposed sections 16, 13, 25 30 19, 14 and 15, thus bringing the carbon coating 12^x on the section 12 into a position engaging the bill form 18^a on the section 18. (See Fig. 9.) The sheet when so folded (see Fig. 1) will bring the bill form 17^a of 35 the section 17 into the topmost position, said printed form being the one form to receive the original inscription or writing. The original inscription or writing upon the printed form 17 will be reproduced through 40 the carbon coatings before mentioned upon the various printed forms of the other sections.

It is apparent that when the sheet is folded in the manner described there will be 45 but a single edge at the top of the folded sections, which edge will permit of a ready and easy introduction of the folded sections to the platen of a typewriting machine.

The multiform billing sheet as illustrated 50 and described is adapted for use in connection with the accounting system of a public service corporation, producing and selling an electric current for various purposes to factories, stores, homes, etc., located in the 55 surrounding territory. The amount of current used by each is recorded by meter and a bill or statement for the amount of electricity used is sent each individual consumer each month.

60 Each meter is numbered and a record of the location and number of each meter is kept on file. Meter readers or inspectors are employed to read the meters and such readings are turned into the accounting department of the corporation. Addressing ma-

chines are used for addressing the folded bill form to the various consumers and at the same time print upon said form the consumer's record or serial number as well as the number of the consumer's meter. After 70 the folded bill form has been so addressed as at 20 in Fig. 1, a typist inserts said folded bill along with a so-called "control sheet" or "general sales sheet" into a typewriter with a carbon coating 16^x on the section 16 75 in contact with the said "control sheet."

Upon the ruled form 17^a of the bill form is typewritten the account number in its proper column along with the last meter reading, and the present meter reading, the 80 difference between said meter readings determining the amount of current used. The rate or cost of the amount of current used is also typewritten upon the folded bill form as is any other item as the occasion demands. The original writing upon the section 17 is reproduced upon various other sections provided with the ruled forms and also upon the "control or general sales sheet" by means of the several carbon coatings before referred to, the carbon coating 16^x in this instance leaving a carbon impression of the writing or inscription upon the said "sales sheet." The folded bill form is then withdrawn from the typewriting machine and 90 the several sections are torn apart along the lines of perforations 11 before referred to. The sections upon which are printed the several ruled forms are then sent, one, viz: the section 17, to the consumer and the rest 100 to the various clerks and book keepers for matter of record. The sections upon which no ruled forms are printed, viz: the sections 10, 15 and 19 may then be destroyed.

In describing my invention I have referred to the specific arrangement for one particular purpose but it is apparent that said arrangement may be modified to meet the requirements of the use demanded without departing from the real spirit of the 110 invention.

What I claim is:

1. A multiform billing sheet adapted to be folded as described consisting of a sheet of paper divided transversely by lines of 115 weakening into eight substantially equal sections, said sheet being provided with printed forms on the second and sixth sections on the obverse face of the sheet and on the third, fifth and seventh sections on the 120 reverse face of the sheet, the printed forms on the obverse face of the sheet being headed toward the top of the sheet and those on the reverse face of the sheet being headed toward the bottom of the sheet and the first 125 and fifth sections of said sheet being provided with transfer material on the obverse face of the sheet and the second, fourth and eighth sections being provided with transfer material on the reverse face of the sheet. 130

2. A multiform billing sheet consisting of a sheet of paper divided transversely by lines of weakening to provide eight sections, said sheet being provided on the second and 5 sixth sections on the obverse face with printed forms headed toward the top of the sheet and on the third, fifth and seventh sections on the reverse face with printed forms headed toward the bottom of the sheet, said sheet 10 being provided with transfer material on the obverse face of the first and fifth sections and on the reverse face of the second, fourth and eighth sections, said sheet being folded back on itself along the line dividing 15 the third and fourth sections and then back along the line dividing the sixth and seventh

sections to bring the seventh and eighth sections back respectively of the first and second sections, being then folded to bring the third section against the reverse face of the 20 eighth section and the two parts thus formed being folded along the line dividing the fifth and sixth sections

In testimony that I claim the foregoing as my invention I affix my signature in the 25 presence of two witnesses, this fourteenth day of October, A. D. 1914.

CHARLES D. MONTAGUE.
